ROTATABLE WHEEL FOR EXERCISING

Albert P. Pellicore, 6952 W. Belmont Ave.,
Chicago, Ill. 60634

Filed Jan. 26, 1973, Ser. No. 326,678

Term of patent 14 years

Int. Cl. D21—01
U.S. Cl. D34—15 G

FIG. 1 is a perspective view of a rotatable wheel for exercising showing my new design;

FIG. 2 is a side elevation thereof;

FIG. 3 is a front elevation thereof; and

FIG. 4 is an enlarged partial cross-sectional view taken substantially at line 4—4 of FIG. 3 and looking in the direction of the arrows thereon.

I claim:

The ornamental design for a rotatable wheel for exercising, as shown and described.
